[57] CLAIM

The ornamental design for a console for self-measuring one's weight, height, blood pressure and pulse rate, as shown.

DESCRIPTION

FIG. 1 is a perspective view of console for self-measuring one's weight, height, blood pressure and pulse rate, showing my new design;

FIG. 2 is a front elevational view thereof;

FIG. 3 is a side elevational view thereof, the opposite side being a mirror image; and

FIG. 4 is a top plan view thereof.

The bottom and the rear of the console is substantially plain and unornamented.

FIG. 1

FIG. 2

FIG. 3

FIG. 4
